[57] CLAIM

The ornamental design for a talking clock, as shown and described.

DESCRIPTION

FIG. 1 is a perspective view of a talking clock showing my new design;

FIG. 2 is a top plan view thereof, the bottom being conventionally plain and unornamented;

FIG. 3 is a front elevational view thereof;

FIG. 4 is a right side elevational view thereof;

FIG. 5 is a left side elevational view thereof; and

FIG. 6 is a rear elevational view thereof.

The broken line depiction of representative time indicia in FIGS. 1 and 3 is illustrative of environment only.
